UNITED STATES PATENT OFFICE.

ABRAHAM J. BEUCUS, OF WAUPUN, WISCONSIN, ASSIGNOR TO PARAMOUNT TEXTILE MACHINERY CO., OF CHICAGO, ILLINOIS, A CORPORATION OF ILLINOIS.

HOSIERY.

Application filed March 11, 1926. Serial No. 93,950.

This invention relates to hosiery and, more particularly, to the type thereof which includes one or more so-called anti-ravel or anti-run back rounds or courses.

It has heretofore been proposed to knit into the plain knitted web of a stocking one or more rounds designed to prevent raveling of the web in the direction in which the knitting progresses so that, in the event of the cutting, breaking, or wearing away of the yarn of the stitches, the fabric beyond a predetermined point will be unaffected.

Scott, No. 1,152,850, dated September 7, 1915—including the type of anti-run back round shown in Fig. 4 of United States Letters-Patent of L. A. Costello No. 976,555, dated November 22, 1910; there also being 60 illustrated in these drawings, diagrammatically, certain of the knitting elements employed in producing the anti-run back course. It is to be understood, however, that my method may be practiced in conjunction with other types of hosiery knitting machines, and with other elements.

The practice generally followed in knitting the anti-ravel round is to throw every other cylinder-needle out of action and float the yarn between the active needles, thus leaving a straight section of yarn between the stitches. This results in the length of yarn in that round being substantially reduced in comparison with that in adjacent rounds, with consequent loss of diametral extensibility of that round. This is a serious defect in that, by reason of the shortness of the diametral dimensions of the round and, thus, of its reduced extensibility, the fabric will frequently rupture in that round. This practice has been followed, almost universally, for certain types of hosiery for a great many years. So far as I am aware, no effective way has yet been suggested of avoiding this defect.

My inventive-concept contemplates departing from the established practice and knitting into the round (in which the reduced number of needles is utilized to produce the same) substantially the same length of yarn as in the proximate rounds, the yarn being floated between stitches, so that that round will be of substantially the same diametral extensibility as the other rounds and, in consequence, will not rupture when stretched, as in use.

The invention involves an improved method of knitting into a hosiery-article one or more anti-run back rounds, the yarn of such rounds being floated between the stitches, the anti-run back round, as well as the proximate rounds, having the same diametral extensibility.

In the accompanying drawings, I have illustrated, diagrammatically, a section of fabric which includes rounds of knitting produced on a so-called Scott & Williams machine—exemplified, for instance, in

United States Letters-Patent of R. W. 55

In these drawings:

Figure 1 is a fragmentary, diagrammatic view, showing the development of the interior of the knitting-cam-cylinder of a Scott & Williams machine and whereby a predetermined number of needles are thrown out of action for knitting the anti-run back round aforementioned;

Fig. 2 is a diagrammatic view, showing a web-holder or sinker and a cylinder-needle coacting therewith to produce a round of stitches, as when all of the needles are in action;

Fig. 3 is a similar view illustrating the relation of the parts in drawing additional yarn to produce the requisite length thereof for the anti-run back round, when half the needles are in action, to produce the required diametral extensibility in that round to correspond with that of proximate rounds, this being accomplished, in this instance by varying the vertical relationship between the sinker or web-holder and the needle;

Fig. 4 is a similar view illustrating the relation of the parts for accomplishing the same result but by varying both the radial and vertical relationship between the sinker or web-holder and the needles; and

Fig. 5 is an exaggerated, diagrammatic view illustrating a portion of fabric which includes a non-raveling round of stitches wherein a section of the yarn is floated between stitches and with my improvement embodied therein.

Referring to the drawings, and to Fig. 1 thereof, the reference-character 1 designates an ordinary stationary cam-cylinder or ring—of a Scott & Williams machine of the type disclosed in said Scott patent—which carries knitting-cams for coacting with butts on cylinder-needles 2 and 3—having butts 2^a and 3^a, respectively—during their stitch-forming operations. The needle-cyl-

110

inder (not shown) is vertically movable with respect to this cam-cylinder and its cams to vary the length of the stitch.

- During normal round-and-round knitting 5 wherein the full set of cylinder-needles in the machine is in action, all of the butts 2^a and 3^a of the needles 2 and 3, respectively, travel on a ledge 4 of the ring 1 in the direction of the arrow Y.
- 10 Where, however, an interposed non-raveling course is to be produced, certain of the needles—being, in this instance, the needles 3—are thrown out of action: To that end, as herein shown, every second needle in 15 the series—being the needle 2—is provided with a jack and is raised thereby, when its jack engages a cam 6, to a relatively higher plane so that its butt 2^a will pass over the top of a cam 7 and engage the upper surface 20 of a cam 9; thence, the butt passes under cams 10 and 11 while its needle takes yarn and forms a new stitch, in the usual manner; whereupon it rises on the slope 12 to the ledge 4. During this operation, the needles 25 3, which have no jacks and which are, then, not to perform knitting, are not raised above the plane of the ledge 4, but ride thereon until they encounter the cam 7 which deflects them under the cam 9 and, thence, 30 under a cam 13 after which they join the active needles 2 and pass therewith up the slope 12 onto the ledge 4.
- It is to be understood that, during normal 35 or round-and-round knitting, all of the needles, 2 and 3, may be drawn to a plane, such as the knitting-line marked A in Figs. 2 and 3; and, thus, both sets of needles assume the same position with respect to the sinkers or web-holders 14. Likewise, where 40 the non-ravel round is to be produced, and for which every second needle (2), as here shown, is raised by its jack, all of the needles (whether in action or not) may be drawn to the same knitting-line A. But the 45 needles 3, whose butts 3^a have not been raised over the cam 8, retain their stitches throughout this operation, while the needles, having butts 2^a, have their latches lifted out of the old stitch and have fresh yarn fed to their 50 hooks so that new stitches are formed thereby. When the needles having the butts 2^a pass down the active face of the stitch-cam 11, they draw the runs of the yarn extending between them down against the hooked 55 ends of needles 3 which, by the operation of the cam 7, have been caused to pass under the cam 9; that is to say, the yarn is floated between the active needles 2 and back of the inactive needles 3. It is an invariable effect 60 of this operation to throw the run of yarn so held behind those needles which did not take it, this being due, in part, to the inward motion of the web-holders which begins during the stitch-forming movement and is completed during the raising of the needles at

the slope 12. It is also an invariable effect that, because only one-half of the number of needles are in action during the knitting of the non-ravel round, and because the same length of loop is drawn by these needles as is drawn by all of the needles during the regular round-and-round work, the length of yarn drawn in the non-ravel round is little more than one-half as long as that drawn in the round when all of the needles are in action. Hence, when the fabric is under diametral extension, this round has to absorb all of the strain and is the cause of frequent rupture of this round and forms the weakest portion of the entire fabric.

The structure illustrated in Fig. 1 is adapted to function in the manner above described and is effective to produce, in one or more courses, the type of stitches shown in Fig. 4 of the aforementioned Costello patent and as explained therein and in the Scott Patent No. 1,152,850.

By my inventive-concept, I am enabled to correct the weakness above pointed out: This I accomplish by providing, in a unique way, for a variation in the relationship between the needles and sinkers and, thus, in respect to the normal knitting-line A. To that end, all of the needles, in knitting the non-ravel round, and whether in or out of action, may be drawn down to a plane, such as the knitting-line marked B in Figs. 2 and 3. Thereby, the reduced number of needles in action will draw longer stitches for the anti-ravel round and sufficient to secure therefor the same degree of diametral extensibility as in the contiguous rounds.

It will be evident that were the length of yarn introduced into the anti-ravel round excessive, the contiguous rounds would be correspondingly weakened thereby, as under diametral extension they would then be required to take undue strain and they would thus form the weak point of the fabric.

In Fig. 5, I have illustrated, in an exaggerated way, the fabric knit by my novel procedure: It is to be understood that rounds A, A, A are those in which all of the needles are employed; and whereby ordinary round-and-round knitting is produced; and that in round B, which is the anti-ravel round wherein every second needle has been thrown out of action and the yarn is floated back of the proximate, inactive needles, the requisite additional length of yarn has been knit into the round. The relation of the sinker or web-holder in respect to the needle in knitting rounds A, A, A may (for instance) be that shown in Fig. 2; while, in knitting my improved anti-ravel round B, the relation of the sinker or web-holder in respect to the needle may (for instance) be that shown in Fig. 3, or in Fig. 4, and whereby the required additional length of yarn is drawn by the needle. In other words, where

the needle is positioned a greater distance except that, in the anti-ravel round, there are below the knitting-line A and, thus, in respect to the active face of the sinker—as shown in Fig. 3—or where the radial movement of the sinker is varied, as well as the vertical movement of the needle, as shown in Fig. 4, the length of yarn forming the B-stitches—here indicated by X—in the B-round, plus the length floated—here indicated by Z—between stitches, should be substantially that used in making the stitches of the A-round plus the length of yarn floated between stitches. Of course, a certain extra length of yarn in the A-round would be absorbed owing to the extra sinuosity of the yarn due to the extra number of needles employed in that round; hence, the yarn in the B-round need not be quite as long as that in the A-round in order to secure the same diametral extensibility in the B-round. It will be noted that, as shown in Fig. 5, in the bottom A-round the intermediate stitches S that have been carried over are shown as drawn longer than normal; but this is done merely to avoid confusion, it being evident that each stitch in a round must necessarily be of the same length when there is no change made in the position of the web-holder or sinker with respect to the needle during the making of that round.

By this disclosure, I present not only a new method of knitting non-raveling fabric, but, also, a new product, in that, in forming a non-raveling course, I vary the knitting relation of the sinkers and needles of which latter only a part are active to produce the course; that is to say, I vary such relationship to maintain a uniform diametral extensibility of the fabric.

It is to be understood that my anti-ravel round is to be distinguished from so-called lace effects, varying gage openwork, etc., and is primarily directed to knitting in which the yarn is floated back of the inactive knitting-needles to produce the type of anti-ravel course shown in Fig. 4 of the aforementioned Costello patent; but, in the present instance, the web of the stocking is of uniform gauge when not under tension, as by stretching; whereas, when tensioned by stretching—as when in use—there is no distortion of the fabric; that is, distortion of the stitches in the anti-ravel round diminishes relatively when placed under tension, as when the stocking is in use. My inventive-concept is directed to a seamless stocking having knit into the body-portion of the fabric thereof and in the leg-section an anti-ravel round, there being rounds of plain knitting on opposite sides of this round, these being integrally connected by that round, so that this round and those at each side thereof involve a continuous and unbroken fabric. It is a feature of the con-

a less number of stitches than in the proximate rounds; but, in this particular round, there is substantially the same length of yarn as in the proximate rounds, so that the diametral extensibility thereof, as well as those of the adjacent rounds, is uniform; hence, the diametral extensibility of all of the fabric is uniform throughout.

What I claim is:

1. A knitted web having a portion of plain knitting including a series of rounds, each round having a predetermined length of yarn knit thereinto, and which determines the diametral extensibility of that round; and a round having a less number of stitches than in the contiguous rounds but with substantially the same length of yarn knit thereinto as in those other rounds, the yarn of that round being floated between stitches, whereby that round is of substantially the same diametral extensibility as the other rounds.

2. A seamless tubular knitted web having a portion of plain-knitting including complete rounds of stitches and an interposed round of knitting comprising stitches half the number of those in contiguous rounds, each stitch containing a greater length of yarn than in the stitches in the contiguous courses, but the course, in its entirety, including substantially the same length of yarn as in the other rounds whereby the diametral extensibility of the fabric in that portion is equal.

3. A knitted web having a portion of plain knitting including an anti-ravel round, a series of rounds at opposite sides of and integrally joined by that round, each round of the series having a predetermined length of yarn knit thereinto and which determines the diametral extensibility of that round, the anti-ravel round having a less number of stitches than in the contiguous rounds but with substantially the same length of yarn as in those other rounds, and the total length of yarn in that round substantially equalling the total length of yarn in each of the other rounds, the yarn of that round being floated between stitches, whereby that round is of substantially the same diametral extensibility as the adjoining rounds.

4. The method of producing seamless hosiery which consists in knitting a series of rounds, each round having a predetermined length of yarn knit thereinto and which determines the diametral extensibility of that round; then knitting a round having a reduced number of stitches but with substantially the same length of yarn as in the other rounds and, at the same time, floating such yarn between stitches; and then resuming the full-stitch rounds, whereby the diametral extensibility of all of the said rounds is uniform throughout.

5. The method of producing seamless hosiery on a series of needles, which consists in knitting a plurality of rounds thereon, each round having a predetermined length of yarn knit thereinto and which determines the diametral extensibility of that round; then throwing every second needle out of yarn-taking position and knitting a round

with one-half the number of stitches but with substantially the same length of yarn ¹⁰ and floating the yarn between said stitches; and then resuming the full-stitch rounds, whereby the diametral extensibility of all of said rounds is uniform throughout.

In testimony whereof I affix my signature.
ABRAHAM J. BEUCUS.
